UNITED STATES PATENT OFFICE.

CARLTON J. STODDARD, OF SALT LAKE CITY, UTAH.

ROOM-COOLING APPARATUS.

1,024,159.

Specification of Letters Patent. Patented Apr. 23, 1912.

Application filed November 6, 1911. Serial No. 658,886.

To all whom it may concern:

Be it known that I, CARLTON J. STODDARD, a citizen of the United States, residing at Salt Lake City, in the county of Salt Lake and State of Utah, have invented certain new and useful Improvements in Room-Cooling Apparatus, of which the following is a specification.

My invention relates to apparatuses for 10 lowering the temperature of rooms during the heated season.

I have aimed to provide a simple and efficient device of a portable nature, which may be placed in any room wherein it is desirable 15 to lower the temperature, that will not only cool the room but will bring into the room pure air from the outside and produce a refreshing circulation of the air within the room, so much desired in sick rooms during 20 the heated season.

I have further aimed to provide an apparatus that will have the appearance of an article of furniture and in which the passage 25 of air through the same may be varied and regulated to secure the temperature desired.

The various uses to which my device may be applied is readily apparent and the form and features thereof may be changed, within 30 the scope of the claim, without departing from the spirit of my invention.

With these objects in view the invention includes the novel construction and arrangement of parts hereinafter described and particularly set out in the claim.

My invention is illustrated in the accompanying drawings in which similar letters of reference indicate like parts throughout the several figures.

Figure 1 is a side elevation with part of 40 the intake pipe cut away. Fig. 2 is a sectional view on line $x-x$ of Fig. 1. Fig. 3 is a transverse vertical section on line $y-y$ of Fig. 1. Fig. 4 is a longitudinal vertical section with the door open and turned back. 45 Fig. 5 is a side elevation of one of the end rests for the drain boards.

An outer casing 1, preferably built of wood and made to resemble an article of furniture, has a lining or inner casing 2 spaced therefrom. The space between the two, except the cover or top, is filled with a non-conductor of heat 3, preferably charcoal, although any good non-conductor of heat may be used. In one end and at the bottom is 50 fitted a door 4, for convenience in cleaning and removing the water tank 5. On the sides

and within said inner casing 2 and spaced therefrom, are the air deflectors 6 which extend from near the top to below the drainboards 7, and preferably to the plane of the center drain 8, which drain has lateral inclinations to the middle and longitudinal inclination toward one end wherein is provided a drain pipe 9. Adjacent the lower edge of each of said deflectors 6 is longitudinally placed two sills 10 which are supported by the uprights 11. Upon said sills 10 rest the cross ties 12 upon which cakes of ice 13 are placed. This manner of supporting the ice allows free air circulation around the ice. At each end of said inner casing 2 is secured the rests or supports 14 which are inclined toward the middle, where upwardly extended lugs 15 are provided. Upon said rests 14 are placed the drain boards 7 with one edge of each against the deflector 6 adjacent. The said drain boards are spaced apart by the said lugs 15. Said drain boards not only act as drains for the water from the melting ice, but also as deflectors for the air currents from around the ice. Below the longitudinally inclined drain 8 is placed the water tank 5, which may have secured thereto a faucet 17 for drawing off the water or which may have a detachable connection 16 fitted in the cover in order to detach said tank from the drain pipe 9 and remove the tank from within the casing 1, through the door 4 which is made close fitting. Through the sides of said casing 1, packing 3 and inner casing 2, are provided ingress and egress openings. The ingress openings 19 are placed near the top of said casings and have fitted therein the intake pipes 20 which are connected with a main intake pipe 21, that leads from without the room. Each side of the device has its respective ingress and egress openings. The egress openings 22 are placed at the bottom of the inner casing 2 in order that there may be complete circulation of air and no dead air spaces.

In using my apparatus I place cakes of ice 13 upon the cross ties and with the ingress pipes open, air will enter the device through the ingress openings 19. This air being warmer than the air in said device, will be directed by the deflectors 6 to the upper portion of the space within the device, as shown by the arrows. This warm air coming in direct contact with the ice, will be chilled or cooled and will fall and the warm air will be drawn downward and be-

tween the spaced apart drain boards 7, where it is again deflected by the drain 8 and out through the egress openings 22 into the room. The continued movement of air 5 through the ingress openings 19 and out through the egress openings 22 will cause a circulation of air through the device and as it passes over and around the ice, it will be cooled. The temperature of the room may 10 be kept as desired by a partial closing of the ingress openings. If they should all be closed as well as the egress openings and the top tightly closed the circulation or air currents will be upward between the deflectors 15 6 and the inner casing, and down through the ice until the air within the device is all of the same temperature and the ice may be kept for considerable time without melting.

Having thus described my invention I 20 desire to secure by Letters Patent and claim:—

A room cooling apparatus consisting of a casing having the walls thereof spaced apart and said space filled with nonheat- 25 conducting material, vertically placed deflector sheets, spaced from the sides of said

casing and extending from near the top to practically the middle of each side, ice supporting means in the upper portion of said casing adjacent the bottom of said deflector 30 sheets, longitudinally placed and laterally inclined drain boards spaced apart and secured below said ice supporting means adapted to direct air currents longitudinally central in said casing, a drain longitudinally 35 and centrally located below said drain boards and adapted to direct the air currents toward the sides of said casing and below said deflector sheets, a plurality of ingress pipes inserted through the sides of 40 said casing and near the top thereof, a pipe connected with said ingress pipe and leading to the outside of the room, and a plurality of egress openings at the bottom of said casing. 45

In testimony whereof I have affixed my signature in presence of two witnesses.

CARLTON J. STODDARD.
